UNITED STATES PATENT OFFICE.

HUGH W. SANFORD, OF KNOXVILLE, TENNESSEE.

RAILWAY CAR.

Application filed December 3, 1923. Serial No. 678,311.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

My improvement relates particularly to mine cars which are to be turned or tilted bodily for the discharge of the contents of the car.

One object of my invention is to produce a mine car which is adapted to be turned or tilted for the discharge of its contents, as above stated, and which has its floor or bottom low relative to the track, in order that for a given head room the car will hold a maximum load, and, for the sake of greater stability of the car on the track, carry the load close to the track rails.

A further object of the invention is to produce a car which possesses flexibility allowing partial twisting or flexing of the car frame to permit one axle of the car to incline out of the horizontal plane of the other axle, in order that all the wheels of the car may at all times bear fully upon the track rails, notwithstanding irregularities in the height of the rails. In this connection it is to be remembered that the axles of many cars of this type are not swiveled but rest in bearings which are fixed on the car body; and in this connection it is further to be remembered that in mining practice the track rails are usually not level nor well supported, a large part of the trackage being temporary and constructed and maintained with the least labor. And it is also to be noted that whenever one wheel of such a car does not rest well on the track, that car is apt to leave the track and thus wreck itself and the train of which it forms a part.

To these ends, the car, in its preferred form, includes strong end sills and strong side sills, and two axles, and a floor or bottom, the side sills having their ends joined to the end sills and said four sills forming a frame of ample strength for resisting all strains, including the weight of the load, end thrust, and longitudinal train pulls, and the axles being combined with the side sills above the bottom of said sills, and the major part of the floor being below the level of the axles and the floor or bottom being so supported as to give the car frame formed

by the end sills and side sills such flexibility as will permit the twisting of the frame to allow the wheels to remain in engagement with the track rails, although there are irregularities in the track, as above mentioned.

The major feature of the supporting of the bottom is the attachment of the ends of the bottom to the end sills, the side edges of the bottom being free or substantially free from the side sills. A secondary feature of such supporting consists in engagement between the bottom and the axles of the car whereby parts of the bottom are supported by the axles.

In the accompanying drawings,

Fig. 1 is a side elevation of a mine car embodying my improvement, parts being broken away;

Fig. 2 is a plan of the same car, parts being broken away;

Fig. 3 is a plan showing the end sills and side sills combined to form the frame of the car, with two axles applied to said frame;

Fig. 4 is an elevation of one end of said frame;

Fig. 5 is an upright longitudinal section on the line, 5—5, of Fig. 3, the bottom plates having been applied;

Figs. 6 and 7 are detail views illustrating the manner of joining the end sills and the side sills;

Fig. 8 is an upright transverse section along the line, 8—8, of Figs. 1 and 2, looking toward the right;

Fig. 9 is an upright transverse section on the lines 9—9, of Figs. 1 and 5, looking toward the right;

Fig. 10 is an upright section on the line, 10—10, of Figs. 1 and 5, looking toward the left;

Fig. 11 is a transverse section on the line, 11—11, of Fig. 5, looking toward the left;

Fig. 12 is a transverse upright section on the line, 12—12, of Fig. 5, looking toward the right;

Fig. 13 is an upright longitudinal section of a form different from the form shown by Fig. 5;

Fig. 14 is a similar detail section of still another form.

Referring first to Figs. 1 to 12, inclusive, A, A represent end sills each having a bumper, A¹, projecting outward therefrom and said sills having a draw bar element, A², also projecting outward from the end sills

and located over the bumper, and the end sills comprising trusses, A³, corner stiffeners, A⁴, and gusset stiffeners, A⁵, all preferably formed of one integral casting.

6 The aforesaid bumper, A¹, is swelled outward as indicated by the drawing, and immediately over the central portion of the bumper is the aforesaid draw bar element, A², provided with a coupling pin opening, 10 A⁶, which is directly over a similar opening, A⁷, of the bumper, a space being left between the draw bar element, A², and the bumper, A¹, for the reception of a coupling link, the coupling pin being designed to drop through 15 the openings, A⁶ and A⁷.

10 The corner stiffeners, A⁴, which have been described as being part of the integral casting, are to be securely riveted to the longitudinal or side sills, B, the sills being slotted 20 as shown at B¹ to afford space for the gusset stiffeners, A⁵.

15 The side sills, B, are to be so heavy as to make them amply strong to resist downward strain or drooping and to resist end- 25 wise thrust and also train pull. At the same time, the frame consisting of the side sills and the end sills must possess sufficient flexibility to allow the axles to incline independently of each other, whereby the car 30 wheels at the same side of the car are allowed to assume different levels to conform to variations or irregularities in level of the track on which the car runs.

35 The two axles, C, are arranged transversely to the side sills and rest in bearings, C¹, secured to the side sills by bolts, C². In the form shown in the drawings, said bearings extend through the side sills and comprise a plate bolted flatwise to the outer sides of 40 the side sills. On each end of each axle is a track wheel, C³. This arrangement brings the axles above the level of the lower edges of the side sills. A sleeve, C⁴, surrounds each axle at its middle and aids in supporting 45 the bottom structure, as will appear further on. The axles and the axle bearings and the axle sleeves together form axle structures.

50 Between the rear end sill and the rear axle, C, and the rear parts of the side sills, B, is a floor plate, D. The rear part of said plate is at the level of the lower edges of the side sills. The forward part of said plate extends obliquely upward and across 55 the rear axle, and then downward in front of that axle nearly to the level of the side sills.

55 The rear edge of said plate is up-turned to form an upright flange, D¹, which rests against the inner face of the rear end sill and is secured thereto by rivets, D². A middle floor plate, D³, extends from the forward end of the plate, D, forward and across the forward axle, C. The rear part 65 of the plate, D³, extends along the level of

the lower edges of the side sills. Then said plate extends obliquely upward and forward across the forward axle, C, and thence downward nearly to the level of the lower edges of the side sills. The rear end of the 70 plate, D³, is upturned to form a flange, D⁴, which under-laps the forward edge of the plate, D. Straps, D⁵, are placed below the axle bearings, C¹, and the axle sleeve, C⁴, in position to bear against said bearings and 75 said sleeves while the plate, D, rests on said bearings and said sleeves. The forward ends of said straps under-lap the rear face of the flange, D⁴, of the middle floor plate, D³. Rivets, D⁶, extend through the rear ends of 80 said straps and the plate, D, and rivets, D⁷, extend through the forward ends of said straps and the flange, D⁴, and the forward edge of the plate, D.

85 A front floor plate, D⁸, extends from below the forward edge of the middle bottom plate forward at the level of the lower edges of the side sills and then upward and obliquely forward to approximately the level of the upper part of the end sill. The 90 rear end of the plate, D⁸, has an upward-directed flange, D⁹, which under-laps the front edge of the middle bottom plate, D³. Straps, D⁵, are applied to the meeting ends of the plates, D³ and D⁸, in the same manner 95 as such straps are applied to the free ends of the bottom plates, D and D³, as already described. The forward edge of the plate, D⁸, is turned downward to form an outward-directed flange, D¹⁰, which bears against the 100 rear face of the forward end sill and is secured thereto by bolts or rivets, D¹¹.

105 The three bottom plates are wide enough to extend from one side sill to the other; and the side edges of said plates have upward-directed flanges, D¹², which stand close to the inner faces of the side sills. But the flanges, D¹², are not secured to the side sills, and said plates are not otherwise secured to 110 the side sills.

115 Thus we have a bottom or bottom structure which has its ends attached to the end sills and is free from the side sills and rests on the axle structure, the axles and the axle bearings being regarded as together forming axles structures. The tendency of the bottom is to bear downward. Hence the middle parts of the bottom structure normally rest on the axle structures. The straps, D⁵, serve to resist tendency to upward movement of the bottom structure when the car 120 is jolted or tilted. In Fig. 13, the straps are omitted and the rear edge of the next forward plate is extended backward under the axle structure to prevent the floor structure 125 from rising.

130 In Fig. 14, the straps and such rearward extension of the next forward plate are both omitted, whereby the middle parts of the floor structure are free to rise.

From the foregoing it will be seen that in these several forms the ends of the bottom structure are secured to the end sills and that the side edges of the bottom structure are free from the side sills. Thus the frame formed by the side sills and the end sills is to the least extent restrained from flexing or twisting to allow all the four wheels of the car to bear fully upon the track rails, whereby danger of derailing the car is reduced to a minimum.

In these several forms, the upward-directed side flanges, D¹², of the bottom plates serve to prevent leakage of coal along the side sills.

While the car above described may be used for sidewise dumping, it is especially designed for discharging from the front end, as by use of a forward tilting tipple. To allow coal to pass over the axles, the forward parts of the first and second bottom plates are made to rise obliquely; and to allow the coal to pass over the front end sill, the forward part of the forward bottom plate or section is made to rise approximately to the height of said end sill. In another application for Letters Patent, executed by me of even date herewith, the entire bottom structure is below the axles and approximately at the level of the lower edges of the side sills, and the side edges of the bottom structure are free from the side sills.

Placing these bottom structures low permits taking a larger load for a given track head room and brings the load closer to the track, whereby greater stability is given to the cars.

From the foregoing description it will be seen that further variations of the structure may be made, the structure yet comprising a car frame having ends and sides and the structure comprising further a bottom or floor secured to the frame ends and free from the frame sides, whereby the frame sides are allowed the largest degree of freedom for flexibility.

I claim as my invention,

1. In a car of the kind described, the combination of a frame, axles transverse to the length of the frame and located above the lower edges of the frame sides, a bottom plate structure supported by the frame ends and the axle structures and parts of said bottom plate structure being at approximately the level of the lower edges of the frame sides and other parts rising to the level of the axles and the forward frame end, and said bottom structure being substantially free from the frame sides, whereby the frame is given freedom for flexing or twisting, substantially as described.

2. In a car of the kind described, the combination of a frame, axles transverse to the length of the frame and located above the lower edges of the frame sides, a bottom

plate structure having flanged edges and being supported by the frame ends and the axle structure and parts of said bottom plate structure being at approximately the level of the lower edges of the frame sides and other parts rising to the level of the axles and the forward frame end and said bottom structure being substantially free from the frame sides, whereby the frame is given freedom for flexing or twisting, substantially as described.

3. In a car of the kind described, the combination of a frame, axles transverse to the length of the frame and located above the lower edges of the frame sides, a bottom plate structure having flanged end edges and being supported by the frame ends and the axle structures and parts of said bottom plate structure being at approximately the level of the lower edges of the frame sides and other parts rising to the level of the axles and the forward frame end and said bottom structure being substantially free from the frame sides, whereby the frame is given freedom for flexing or twisting, substantially as described.

4. In a car of the kind described, the combination of a frame, axles transverse to the length of the frame and located above the lower edges of the frame sides, a bottom plate structure supported by the frame ends and extending across and resting on the axle structures, and parts of said bottom plate structure being at approximately the level of the lower edges of the frame sides and other parts rising to the level of the axles and the forward frame end and said bottom structure being substantially free from the frame sides, whereby the frame is given freedom for flexing or twisting, substantially as described.

5. In a car of the kind described, the combination of a frame, axles transverse to the length of the frame and located above the lower edges of the frame sides, a bottom plate structure comprising a plurality of plates and being supported by the frame ends and extending across and resting on the axle structures, and parts of said bottom plate structure being at approximately the level of the lower edges of the frame sides and other parts rising to the level of the axles and the forward frame end and said bottom structure being substantially free from the frame sides, whereby the frame is given freedom for flexing or twisting, substantially as described.

6. In a car of the kind described, the combination of a frame, axles transverse to the length of the frame and located above the lower edges of the frame sides, a bottom plate structure comprising a plurality of plates meeting each other at the axles and supported by the frame ends and extending across and resting on the axle struc-

- 4
- tures, and parts of said bottom plate structure being at approximately the level of the lower edges of the frame sides and other parts rising to the level of the axles 5 and the forward frame end and said bottom structure being substantially free from the frame sides, whereby the frame is given freedom for flexing or twisting, substantially as described.
- 10 7. In a car of the kind described, the combination of a frame, axles transverse to the length of the frame and located above the lower edges of the frame sides, a bottom plate secured by its rear edge to the 15 rear frame end at approximately the level of the lower edges of the frame sides and having its forward end at the height of and supported by the rear axle structure, and a second plate extending from and supported by the rear axle at approximately the level of the lower edges of the frame sides and extending to the height of and supported by the forward axle structure, and a forward bottom plate extending from 20 and supported by the forward axle structure at approximately the height of the lower edges of the frame sides and having its forward end at approximately the height of the forward frame end and secured to 25 said end, and the side edges of said plate being substantially free from the frame sides, whereby the frame is given freedom for flexing or twisting, substantially as described.
- 30 8. In a car of the kind described, the combination of a frame, axles transverse to the length of the frame and located above the lower edges of the frame sides, a bottom plate secured by its rear edge to the rear 35 frame end at approximately the level of the lower edges of the frame sides and having its forward end at the height of and supported by the rear axle structure, and a second plate extending from and supported 40 by the rear axle at approximately the level of the lower edges of the frame sides and extending to the height of and supported by the forward axle structure, and a forward 45 bottom plate extending from and supported by the forward axle structure at approximately the height of the lower edges of the frame sides and having its forward end at the height of the forward frame end and secured to said end, and the side edges of said plate being substantially free from the frame sides, whereby the frame is given freedom for flexing or twisting, substantially as described.
- 50 9. In a car of the kind described, the combination of a frame, axles transverse to the length of the frame, and a bottom structure comprising three plates each having its rear end lower than the axles and the forward ends of the rear and middle plates rising to the height of the axles and the forward end of the forward plate rising to the height of the forward frame end and the meeting ends of said plates being joined to each other, and the rear end of the rear plate being joined to the rear frame and the forward end of the forward plate being joined to the forward frame end, and the side edges of said plate being substantially free from the frame sides, whereby the frame is given freedom for flexing or twisting, substantially as described.
- 55 10. In a car of the kind described, the combination of a frame, axles transverse to the length of the frame and supporting the frame sides, a bottom plate structure supported by the frame ends, and extending below the level of the frame ends and rising to approximately the level of the axles and the level of the forward frame end and said bottom plate structure having its side edges substantially free from the frame sides, whereby the frame is given freedom for flexing or twisting, substantially as described.
- 60 11. In testimony whereof I have signed my name, this 28th day of November, in the year one thousand nine hundred and twenty-three.

HUGH W. SANFORD.
